Inventor:

ALBERT A. SORG

Att. J. Miller

ATTORNEY

BY

UNITED STATES PATENT OFFICE.

ALBERT A. SORG, OF GRAND RAPIDS, MICHIGAN.

LADDER.

1,377,977.

Specification of Letters Patent.

Patented May 10, 1921.

Application filed August 30, 1919. Serial No. 320,962.

To all whom it may concern:

Be it known that I, ALBERT A. SORG, a citizen of the United States, residing at Grand Rapids, in the county of Kent and 5 State of Michigan, have invented certain new and useful Improvements in Ladders, of which the following is a specification.

My invention relates to improvements in extension ladders, and more particularly in 10 that class of ladders that is used for constructing painter's platforms or stagings, heretofore secured to me by Letters Patent of the United States numbered 487,302, issued December 6, 1892, and manufactured 15 and sold by me, and its objects are: first to provide a means whereby the extension may be made to, at all times, move directly upwardly or downwardly when extending or withdrawing the extended section thereof; 20 second, to provide a means whereby the extended section of the ladder will be, automatically, locked into position when properly adjusted; third, to provide a means whereby the link braces will be held from 25 lateral movement when the ladder is adjusted for use, and, fourth, to provide a means whereby the ladder may be folded into compact form for storing &c.

I attain these objects by the mechanism 30 illustrated in the accompanying drawing, in which Figure 1 is a side elevation of the ladder folded for storing, conveying, &c. Fig. 2 is a side elevation of the ladder with the parts extended in position for use. Fig. 35 3 is a front elevation of the ladder. Fig. 4 is a front elevation, and Fig. 5 is a side elevation of the governing slide as it is applied to the extensible section of the ladder. Fig. 6 is a top plan of the same with its several 40 connecting elements in position thereon. Fig. 7 and Fig. 8 are edge views of the actuating links that support the extended lower sections of the ladder. Figs. 9 and 10 are plans of the same.

45 In the construction of this ladder the ladder standards or sections 1 and the extension section 2 are old in my ladder hereinbefore mentioned. The new elements in this ladder consist, first, of the slide member 3 which is made of steel or other suitable 50 sheet metal and has a cross piece 7 that is pivotally connected with the stiles 1 of the lower sections of the ladder, as at d, so that said lower sections may be folded closely to 55 the extension standard 2, as in Fig. 1, or may be extended or swung outwardly therefrom,

as in Fig. 2 to form a firm supporting base for the ladder. This slide has two links 4 and 4' that are pivotally connected together at e, are pivotally connected with the 60 stiles 1 as at b, and are adapted to be moved upwardly or downwardly at their connected ends by means of the bolt 12 acting in the slot 5, in the slide 3. The slide 3, at one side of the slot 5, is offset to form a second plane 65 with sufficient distance between the offset 3' and the normal outer surface of the slide so the end of the link 4' may pass freely between them so as to avert any possible danger of lateral movement of the connected 70 ends of the links. The link 4 has the movable end curved around and extended backwardly, as at g, for the purpose of forming a convenient handle with which to operate the links. These features constitute the 75 means whereby the slides 3 are secured to the stiles 1. The slides are, also provided with backwardly extending wings f that are adapted to extend backwardly over the edges of the stiles 2 to form readily adjustable 80 slideways and guideways for said stiles.

The locking element in this construction consists of a diagonal wing formed integral with one edge of the slides and having a slot, 85 6, therein that inclines outwardly and upwardly from the edge of the stile 2. There being a slide on each side of the ladder, and corresponding slots in said slides, I place a bolt or rod 8 across the ladder with one end supported in each of said slots. The slots 90 6 are so formed that when the rod 8 is carried upwardly in the slots the stiles 2 may be moved freely either upwardly or downwardly without contacting with the rod, but the lower end of the slots will carry the rod 95 back of the surfaces of the stiles, and the stiles are provided with indentures a into which the rod may drop so that the action of the rod in said indentures and pressing the stile against the bearings f of the slide 100 will lock the stiles firmly in any given position they may be placed. If it is desired to raise the extensible section of the ladder it is simply necessary to take hold of a rung 11 and lift it upwardly and the rod 8 will 105 be displaced from the indenture and the section may be raised to the desired height and anchored in place by dropping it downwardly in position so the rod will rest in corresponding indentures. If desiring to 110 lower the section it must be first raised upwardly sufficiently to release the rod from

the indentures. The rod must then be held in place and the section lowered into the desired position, when the rod is to be allowed to locate itself in the indentures, when the 5 section will be firmly locked in place. The steps 9 and 10 may be secured to the stiles 1 by any available means.

It will be readily understood that with this construction, or its near equivalent, the 10 vertical movement of the adjustable section of the ladder must be directly upwardly or directly downwardly, and it cannot, by any possibility, be made to incline in either direction from the perpendicular when the 15 base sections, 1, are properly placed, and the secure manner in which the brackets are secured to the steps and to the stiles renders it impossible for the ladders to become 20 slimy sidewise, thus rendering the ladder absolutely rigid and firm in every direction.

I find it advisable to place metal reinforcing pins, or protecting elements, as h , at the upper edges of the indentures a to avert the danger of so wearing the stiles at these 25 points as to render them unsafe when heavy loads are to be supported upon the extension sections of the ladder.

What I claim as new in the art, is:

1. In combination with a step ladder having a vertically adjustable center section, 30 lower sections supporting the center section; a slide pivotally mounted upon the upper ends of the lower sections, links pivotally connected with the lower sections, pivotally

connected together, and slidably connected 35 with the slides, said slides having slots that incline from the perpendicular, a rod mounted in said slots, and indentures formed in the edges of the stiles of the central section of the ladder to receive the rod 40 and lock the ladder extension in place.

2. In combination with the supporting base sections, and the vertically adjustable center section of an extension ladder, a slide pivotally connected with the upper ends of 45 the base sections, said slide having a vertically disposed slot centrally located, and an outwardly inclined diagonal slot near one side, the metal at one side of the vertical slot offset to form a lateral slot between the 50 surface of the slide and the surface of the offset metal, a link pivotally connected at one end with one of the base stiles, the other end passed through the lateral slot and pivotally connected with another link, 55 the other end of the last named link pivotally connected with the stile of the other base section, a bolt passed through the ends of the two links and through the vertical slot in the slide, the central section of the 60 ladder having indentures in the edges of the stiles, a rod mounted in the inclined slots in the slides to engage the indentures in the stiles and lock the central section of the ladder in desired positions.

Signed at Grand Rapids, Michigan, Au-
gust 25, 1919.

ALBERT A. SORG.
